UNITED STATES PATENT OFFICE.

ADOLPH N. WALSTAD, OF TACOMA, WASHINGTON.

HINGE.

Application filed April 6, 1925. Serial No. 21,012.

This invention relates to hinges and has special reference to a hinge which permits a relative sliding and turning movement between the bodies to which it is attached. 5 The particular use to which this hinge is intended to be applied is as a connection between a filler leaf for extension tables and the two sections of the table top between which the filler leaf is mounted. 10 The objects of the invention are to provide such a hinge which will support the filler leaf from the table top in such manner as to permit the filler leaf to be in the same plane as and between the two sections 15 of the table top or to be swung thereunder and stowed away in the space below the table tops; which will permit said filler leaf to be just as wide as the said space under said sections will allow; which is 20 ably mounted on said filler leaf and the table top; which is limited in its motion on each said parts; which will positively tie the two halves of the table top together and will not permit them to be separated sufficiently to 25 pull the sliding parts out of their guides; and which will permit the table tops to be opened wide enough to permit the usual dowel pins to be used between the table top parts and the filler leaf. Further objects 30 are to provide a hinge which is cheap to make and to apply; easy to operate; effective in use; and which will not easily get out of order or repair.

I attain these and other objects by the 35 devices, mechanisms and arrangements illustrated in the accompanying drawings, in which—

Fig. 1 is a cross-section of a table top in closed position, showing two of my hinges 40 in position thereon; Fig. 2 shows the parts in the positions occupied when the table is partway opened; Fig. 3, when fully opened and the filler leaf still in stowed away position; Fig. 4, when the filler leaf is raised; 45 and Fig. 5, when the table top sections are closed thereon to form an extended table; Fig. 6 is a plan view of the sliding plates forming one hinge; Fig. 7 is a cross-section of the end of the guide which is secured to the under side of the table top; and Fig. 8 is 50 a longitudinal section thereof, to show the stop at the end thereof.

Similar numerals of reference refer to 55 similar parts throughout the several views.

The operation of the table will first be 55 briefly described. The table comprises two

top sections 1 and 2, suitably supported and slidably connected together in the usual manner and each provided with suitable vertical aprons 3. The filler leaf is preferably made 60 with two pieces 4 and 5, divided longitudinally of the table, that is to say at right angles to the joint between the two parts 1 and 2 of the table top, and suitably fastened together by hinges or other means 65 which are not illustrated herein as they form no part of this invention. The part 4 is fastened to the table tops 1 and 2 by a pair of my improved hinges, hereinafter described, and the part 5 lies below it when in 70 stowed position (Figs. 1, 2 and 3) and in the same plane when in extended position (Figs. 4 and 5). Dowel pins 6 extend from one table top section 2 and enter holes in the other section 1, or in the filler leaves 4 and 5, while similar dowel pins 7 extend from corresponding points in the filler leaves 4 and 5 and enter the same holes in said table 75 top section 1.

Referring, now, to Fig. 1 it will be seen 80 that the width of the filler leaves 4 and 5, together with their dowel pins 7, fill up the entire width of the space between the aprons 3, when stowed away and the table is in closed position. Also, referring to Figs. 85 3 and 4 it will be seen that the table top sections 1 and 2 must be separated from each other by a space greater than the width of the filler leaves 4 and 5 by a distance 90 slightly more than the sum of the distances 95 which the dowel pins 6 and 7 extend from their respective surfaces, therefore their movement apart must be greater than the distance between the aprons 3 by more than the length of the dowels 6. But, since the 100 total length of the two hereinafter described guides, which are secured to the under sides of the table top sections 1 and 2, must be less than the distance between the said aprons 3 and, since it is also necessary that the hinge 105 plates in said guides have some effective length in addition, it is evident that the hinge plates must also slide on the filler leaves to allow for the extra distance which the table top sections move, and this is the 110 condition which this form of hinge is especially designed to fulfill.

Referring next to the hinge itself, it will be first understood that usually two of these 115 hinges will be used, said hinges being coaxially located and turned to occupy correspondingly reversed positions. One only

such hinge will therefore be described. On the under side of the table top section 1 is secured a guide plate 8 whose axis is at right angles to the joint between the table top sections 1 and 2. This plate 8 extends from the apron 3 practically to the center line of the table, and is provided with two down-and-in turned flanges 9 which support the sliding hinge plate and which are separated 5 by a sufficient space to permit the hinge lug to pass freely between them. These flanges 9 extend from end to end of the plate 8 and are provided, at the end adjacent to the center line of the table, with stops 10 adapted 10 to be engaged by the shoulder of the hinge plate to prevent the said hinge plate from being pulled out from said guide when the table is opened. A second guide plate 11 is secured to the under side of the filler leaf 20 4, in line with the above-mentioned guide plate 8, and is of similar section but may be made much shorter in length and is not provided with any stops such as the above described stops 10. The plates 8 and 11 may 25 be secured in place by means of screws or any other desired means, provided that the heads thereof do not interfere with the free movement of the hinge plates in the channels of the guides.

30 Each hinge proper is in two sections, a short section 12 adapted to engage the guide 8 and to be supported thereby, and a long section 13 adapted to engage the guide 11 and to be supported thereby. Each such 35 section 12 and 13 comprises a straight plate which has a downturned ear or lug 14 and 15, respectively, and these two lugs are pivoted together by means of the hinge pin 16 passing through them. The plates 12 and 13 are cut at their adjacent ends to form 40 shoulders 17 and to permit the lugs 14 and 15 to pass between the flanges 9 on the respective guides 8 or 11. The shoulders 17 on the plate 12 are adapted to engage the 45 stops 10 on the guide 8. The plate 13 is provided with a central elongated slot 18 with closed ends 19 and 20, and with a narrow tail lug 21 which is bent down therefrom and provided with a suitable hole for 50 the spring 22, hereinafter described.

The plate 12 is mounted in the guide 8 with its lug 14 towards the center of the table, and the plate 13 is mounted in the guide 11. A stop pin 23 is passed through 55 the slot 18 and into the filler leaf 4 in such position that when the table is closed (Fig. 1) the stop 23 will engage the inner end 19 of the slot 18 and, in this position, the end of the plate 12 is at the extreme end of the guide 8 and practically touching the apron 3. Also, in this position, the plate 13 has 60 been slid back over the filler leaf, away from the joint, so that the edge of the filler leaf, or the ends of its dowels 7, practically 65 touch the same apron 3 and are thus sub-

stantially in the same plane as the end of the plate 12. The length of the slot 18 in the plate 13 is such that when the table is opened sufficiently to permit the filler leaf to swing freely (Figs. 3 and 4) the stop pin 23 is in engagement with the other end 20 thereof (Fig. 2) so that, in this position, the hinge plates prevent the further separation of the table top sections through the engagement of the stop lugs 10 with the shoulders 17 and the stop pins 23 with the slot ends 20. In this position, therefore, the plates 12 have slid the length of the guides 8, as far as the stops 10 will permit them, and the plates 13 have slid the length of the slots 18. The stop 10 and shoulder 17 are so positioned as to permit the hinge lug 14 to extend slightly beyond the plane of the edge of the table section, thus permitting the corners of the plate 13 to pass the edge of the table top without scratching it. This effect is further insured by means of the springs 22 secured to the lugs 21 and to suitable pins 24 in the filler leaf 4 to pull the said hinge plates towards the center of the filler leaf.

Thus it will be seen that my improved hinge permits of a greater movement of the table tops than the combined length of the slides 8, on the under sides thereof, by permitting the hinge to float between the parts hinged together thereby; and by limiting the extent of such floating movement it prevents the table from being opened wide enough to drop the filler leaves by allowing the floating hinge parts to be pulled out of their supporting guides. It will also be observed that the filler leaf is permanently attached to the table; that it is suspended by substantial means at a predetermined distance below the table top when not in use; that the hinges are permanently attached to each hinged part and yet floats therebetween; that each hinge comprises a pair of flat plates mounted on the under sides of the hinged parts; and that each such plate is provided with an ear which cooperates with the corresponding ear of the other plate to form the holder for the hinge pin thereby removing the axis of the hinge away from the undersurfaces of the table top and filler leaf, thus protecting the upper surface of the filler leaf from being injured by contact with the table top when stowed away.

Having therefore described my invention, what I claim is:—

1. A hinge adapted to secure two bodies together, comprising a hinge plate slidably mounted on one body; a complementary hinge plate slidably mounted on the other body; and a pivot pin connecting both said hinge plates together, whereby said two bodies are secured together and one body is permitted a slidable and revoluble movement with relation to the other body.

2. A hinge plate adapted to secure two bodies together, comprising a hinge plate slidably mounted on one body and having a lug extending at right-angles thereto; a complementary hinge plate slidably mounted on the other body and having a complementary lug extending therefrom; and a pivot pin connecting both said lugs to hinge the plates together, whereby said two bodies are secured together and one body is permitted a slidable and revoluble movement with relation to the other body.
3. A hinge adapted to secure two bodies together, comprising two separate guide plates each fixedly secured to one of said bodies in axial alinement with each other; together with a floating hinge comprising two parts pivotally secured together and each part slidably mounted on one of said
- guide plates whereby the two bodies are secured together in slidable and revoluble relation.
4. A hinge adapted to secure two bodies together, comprising two separate guide plates each fixedly secured to one of said bodies in axial alinement with each other; a pair of separate complementary hinge plates, each slidably supported in one said guide plate, each having complementary hinge lugs extending at right-angles thereto; and a pivot pin passing through both said lugs, whereby the two hinge plates form a hinge body floating in said guide plates, and whereby the two bodies are secured together in simultaneously slidable and revoluble relation.

ADOLPH N. WALSTAD.
